Patented Dec. 20, 1960

189,465

BOAT STEERING UNIT

John W. Edgemond, Jr., San Jose, Calif., assignor to
Food Machinery and Chemical Corporation, San Jose,
Calif., a corporation of Delaware

Filed Jan. 6, 1960, Ser. No. 58,943

Term of patent 14 years

(Cl. D71—1)

FIG. 1

FIG. 2

FIG. 3

FIG. 4

Fig. 1 is a front perspective view of a boat steering unit embodying my new design; and

Fig. 2 is a rear perspective view thereof.

Fig. 3 is a plan of the unit.

Fig. 4 is an elevation of the unit.

I claim:

The ornamental design for a boat steering unit, as shown.
